OPHTHALMIC MOUNTING

Earle J. R. Beattey, Edgewood, R. I., assignor to
Universal Optical Corporation, Providence,
R. I., a corporation of Rhode Island

Application August 16, 1930. Serial No. 475,689

6 Claims. (Cl. 88—43)

This invention relates to an improved construction of ophthalmic mounting; and has for its object to provide a bridge for connecting together the lens-engaging members, the bridge being so constructed that it has bendable arms of a substantial length for adjusting the pupillary distance of the lenses, the arms being also provided with downwardly-extending end portions of a substantial length providing extended surfaces for attachment to the lens-engaging members.

A further object of the invention is to form double side arms on the cross bar portion of the bridge, which extend first rearwardly a substantial distance, and then forwardly being connected by a return bend and both arms being in substantially the same plane as that of the cross bar, the ends of these side arms being turned downwardly at substantially right angles to its arm to extend along the sides of the eye-wires or lens mounting to provide an extended attaching surface for rigidly securing these ends to the lens-engaging members.

The invention further consists in the extending of these attaching side arm portions down to a point adjacent the medial line through the lenses and to mount a pair of nose guards independently of the bridge on the eye-wires on substantially the medial line through the lenses.

With these and other objects and advantageous features in view, the invention consists of a novel arrangement of parts more fully disclosed in the detailed description following, in conjunction with the accompanying drawing, and more particularly set forth in the appended claims.

In the drawing:

Fig. 1 is a front view of my improved construction of bridge and nose guard members, showing the side arms of the bridge as extending down adjacent the medial line through the eye-wires;

Fig. 2 is a top edge view illustrating the end portions of the cross bar of the bridge and extending rearwardly and then forwardly and connected by a return bend;

Fig. 3 is a perspective view showing the end fold of each side arm as extending downwardly providing an extended surface for attachment to the eyewires;

Fig. 4 is a perspective view showing both the rearwardly and forwardly extending portions of the side arms as being in substantially the same plane as that of the bridge cross bar of the bridge;

Fig. 5 is a perspective view of one of the nose guards detached.

It is found in practice that usually many sizes of mountings have to be carried in stock by the dealer in order to accommodate the widely varying shapes of faces of the different wearers and where these frames are made of the precious metals a considerable investment is required to carry a full line of such mountings, in order to obviate the necessity of carrying so large a stock. I have constructed a mounting in such a way that it may be readily adjusted over quite a wide range and so reduce to a great extent the number of different sizes required to be carried in stock. To this end I have formed the cross bar of the bridge member with double length bendable side arms connected by a return bend, which arms are adapted to be bent in any direction to adjust the pupillary distance of the mounting to suit the different wearers; also, in order to provide a strong joint between the bridge and the lens-engaging members, I have caused the ends of these side arms to extend downwardly for a substantial distance along the eyewire or lens-engaging member to offer an extended surface for such attachment; also, I preferably extend the lower ends of these attaching members down to a point adjacent the medial line through the lenses leaving sufficient space at their lower ends to permit the guard members to be attached thereto on this medial line through the lenses; whereby the guard member being adjustable independently of the adjustment of the bridge to properly support the mount on the face of the wearer; and the following is a detailed description of the present embodiment of my invention and showing one means by which these advantageous results may be accomplished.

With reference to the drawing, 10 designates the lenses, and 11 one form of lens-engaging member, in this particular instance eyewires are shown, and these eyewires are shown as being connected by a bridge member 12. This bridge member is preferably formed from a length of wire and folded to provide a cross bar 13. The ends 14 of the cross bar are disposed to extend rearwardly for a substantial distance, and each of these arms is provided with a return bend 15 with forwardly extending arm portions 16. The end portions of these arms are turned downwardly as at 17 to extend a substantial distance along the eyewire 11 providing an extended attaching surface by which these end portions 110

may be rigidly secured to the edge of the eye-wire, or other lens-engaging member.

These side arms 14 and 16 are preferably folded to lie in substantially the same plane as that 5 of the cross bar 13 which renders them much less conspicuous than when extending on an inclined plane; also, by this construction, these side arms may be formed of an extended length, thereby permitting wide variation in adjustment 10 for pupillary distance of the different mountings.

These downwardly extending side arm portions are preferably positioned so that their lower ends will terminate just above the medial line 18 through the lenses and by this construction 15 the bendable arm 19 of the nose guard 20 may be attached on this medial line, which is of importance to mountings of this construction. Also this arm 19 of these nose-guard members is formed bendable so that the nose-guard may be 20 adjusted independently of the bridge member to fit and properly engage the noses of different wearers which vary to a considerable extent.

By this adjustment, the number of different sizes of mountings to be carried in stock may be 25 greatly reduced, thus materially reducing the investment in stock of the dealer, which is of considerable importance, particularly where the mountings are of precious metals and also by this independent adjustment of the bridge member 30 and the nose guards, accurate fitting of the mounting to the faces of the different wearers is permitted.

While I have described certain construction forms which embody the principles of my invention, it is obvious that other desired changes 35 in arrangement may be made within the spirit and the scope of the invention as defined in the appended claims.

I claim:

- 40 1. An ophthalmic mounting having spaced eyewires, a high bridge connecting said eyewires, said bridge being provided with a cross bar having a rearwardly extending arm folded upon itself at each end thereof, both folds of said arms being disposed in substantially the same horizontal plane and in the same plane as said cross bar, the end portions of said arms extending downwardly a substantial distance along the eyewires providing an extended attaching surface.
- 45 2. An ophthalmic mounting having spaced eyewires, a high bridge connecting said eyewires formed of a length of wire folded to provide a cross bar portion having at each end thereof and in the horizontal plane therewith a rearwardly extending bendable arm folded upon itself to provide two parallel parts with its two parts

connected by a return bend, the end portions of each arm extending downwardly a substantial distance to a point adjacent the medial line through the eyewires, said downwardly extending portion providing an extended surface for 80 attachment to the eyewires.

3. An ophthalmic mounting having spaced eyewires, a horizontal bridge member connecting said eyewires, said bridge member being provided with end portions extending rearwardly 85 and in the same horizontal plane therewith, each being then folded upon itself forming bendable double substantially parallel side arms, the free end portions of the return arm portion extending downwardly substantially at right angles to the plane of said arms substantially to the medial line through the lenses, and a pair of nose guards supported on the mounting adjacent the attaching ends of the bridge.

4. An ophthalmic mounting having spaced 95 eyewires, a bridge connecting said eyewires being formed of a length of bendable wire folded to form a cross bar having rearwardly extending arm portions each folded upon itself to provide forwardly extending portions, both parts of the 100 arm being disposed in substantially the same horizontal plane as that of the cross bar the end portions of said arms extending downwardly along said eyewires a substantial distance providing an extended surface for attachment. 105

5. An ophthalmic mounting having spaced 110 eyewires, a bendable bridge connecting said eyewires, said bridge comprising a cross bar with its end portions extending rearwardly in substantially the same horizontal plane as that of the cross bar, and then doubled and extending forwardly to provide double side arms connected by a return bend the end portions of said arms 115 extending downwardly along said eyewire a substantial distance and a pair of nose guards attached to said eyewires at the lower ends of said end portions.

6. In an ophthalmic mounting, a pair of lens-engaging members, a bendable bridge formed of a length of wire having a cross bar member with 120 end portions extending rearwardly and then forwardly forming a double arm connected by a return bend, both parts of the double arm being in substantially the same plane as the cross bar, the end portions of these arms providing an 125 extended surface for attachment to said lens-engaging members, and nose guard plates each having a forwardly extending bendable arm attached to said lens-engaging member. 130
